[57] CLAIM

The ornamental design for a watch dial, as shown and described.

DESCRIPTION

FIG. 1 is a front elevational view of a watch dial showing my new design;
FIG. 2 is a rear elevational view thereof;
FIG. 3 is a top plan view thereof, the bottom being the same in appearance as the top; and,
FIG. 4 is a right side elevational view thereof, the left side being the same in appearance as the right side.

FIG. 1

FIG. 4

FIG. 2

FIG. 3
